UNITED STATES PATENT OFFICE.

JAMES MASKER, OF HAMMOND, INDIANA.

RAILWAY-CAR ROOF.

No. 903,240.

Specification of Letters Patent.

Patented Dec. 1, 1908.

Application filed April 13, 1907. Serial No. 367,947.

To all whom it may concern:

Be it known that I, JAMES MASKER, a citizen of the United States, residing at Hammond, in the county of Lake, State of Indiana, have invented a new and useful Improvement in Railway-Car Roofs, of which the following is a full, clear, and exact description, reference being had to the accompanying drawings.

- 10 My invention relates to new and useful improvements in car roofs of that class commonly known as "outside roofs", and particularly contemplates the provision of a construction in which the main elements 15 thereof will securely hold in water-tight relation while allowing the same sufficient play to overcome the tendency of the same to buckle and bend under the effect of the strain put upon them.
- 20 My invention further and specifically resides in the following features of construction and arrangement as will be hereinafter described with reference to the accompanying drawings forming a part of this specification, in which like numerals are used to 25 designate like parts throughout the several figures, and in which,

Figure 1 is a perspective view of a portion of a car roof constructed in accordance with 30 my invention, Fig. 2 is a perspective view of one of the intermediate roof plates, Fig. 3 is a similar view of one of the end roof plates, Fig. 4 is a bottom plan view of one of the carlines, Fig. 5 is a side elevation of 35 the same, Fig. 6 is an end view of the same, Fig. 7 is a perspective view of one of the plate securing clips, Fig. 8 is a similar view of one of the carline end caps, Figs. 9, 10 and 11 are perspective views of adjoining 40 sections of the ridge pole, Fig. 12 is a perspective view of the ridge pole securing plate. Fig. 13 is a sectional view taken through one of the flanges of the roof plates on an enlarged scale, and Fig. 14 is a trans- 45 verse sectional view taken through my improved roof as a whole.

In the practical embodiment of my invention and with particular reference to the accompanying drawings I provide a ridge 50 pole comprising detachable sections B', B² and B³, the intermediate section B³ being provided with mortised and reduced ends B⁴ and B⁵ respectively, engaging with the 55 respectively mortised and reduced adjacent ends B⁶ and B⁷ of the outer pieces B' and B². The outer ends B⁸ of the end pieces B'

and B² are also reduced to receive thereon the ridge pole cap plates C¹ which are bolted or otherwise secured to the ends of the car. The pieces B', B² and B³ forming the ridge pole are further provided with longitudinal undercut channels B⁹ and with openings B¹⁰ communicating with said channels B⁹, for the reception of the reduced ends E⁵ of the carlines E⁸. The carlines E⁸ are also reduced upon their outer ends E⁶ to receive thereover the carline end caps C⁴ bolted or otherwise attached to the car sides. The carlines E⁸ are further provided with longitudinal parallel channels E⁷ for a purpose 70 to be hereinafter described.

A plurality of metallic plates D⁵ have flanges D⁸ bordering the same, said flanges having the edges thereof curled about metallic rods D⁴ to strengthen the same. The 75 side flanges and one end flange are constructed upstanding from their respective plates and have their abutting ends soldered together, said end flange being adapted to be held within the channels B⁹ of the ridge 80 pole, and said side flanges being adapted to be held within the channels E⁷ of the carlines E⁸ when said plates D⁵ are inserted therebetween thus forming with said ridge pole and said carlines, a movable though 85 perfectly water-tight joint. The description of the plates thus far applies to the intermediate plates D⁵ while the end plates D⁶ and D⁷ have only their inner end and side flanges D⁸ upstanding, the remaining flanges 90 D⁹ like the outer end flanges D⁸ of the plates D⁵ being turned down upon the car sides and ends, and secured thereto by metallic clips F⁹ engaging the curled edges of the said flanges D⁹ and secure to the car. 95

In securing the ridge pole upon the car I provide the pieces B', B² and B³ with longitudinal beveled lower edges B¹¹ adapted to slidably fit within the undercut channel A² of securing plates A' adapted to be bolted 100 to the top of the car thus effectually covering the bolt openings and preventing moisture entering the car by this means. I also cast the pieces B', B², and B³ with upstanding ledges G¹⁰ which may be utilized as 105 sleepers for the well known walking boards (not shown).

From the foregoing description it will be apparent that I provide a novel construction of an outside roof for cars in which the several elements are securely held in place and form perfectly water-tight joints while hav-

ing sufficient movement with relation to one another to overcome the tendency of breaking apart and of the metallic plates buckling and bending under the strain imposed upon 5 them by the moving car.

Having thus fully described my invention, I claim:

1. The combination in a car roof, of a ridge pole, and means for securing the same 10 comprising a clamping plate rigidly secured upon the car and adapted to receive said ridge pole therein and to clamp the sides thereof, substantially as described.

2. The combination in a car roof, of a 15 ridge pole, and means for securing the same comprising a clamping plate rigidly secured

upon the car and provided with a channel adapted to receive and hold said ridge pole therein, substantially as described.

3. In a car roof of the character described, 20 the combination of a ridge pole formed in length by a plurality of relatively engaging sections, and dove-tailed guide plates secured upon the car for clamping each of said sections, substantially as described.

In witness whereof I hereunto affix my signature in presence of two witnesses this 8th day of April, 1907.

JAMES MASKER.
